UNITED STATES PATENT OFFICE.

WILLIAM BRADLY, OF PHILADELPHIA, PENNSYLVANIA.

DESIGN FOR A FLAG.

SPECIFICATION forming part of Design No. 22,306, dated March 28, 1893.

Application filed January 24, 1893, Serial No. 459,603. Term of patent 14 years.

To all whom it may concern:

Be it known that I, WILLIAM BRADLY, a citizen of the United States, residing in the city and county of Philadelphia, State of Pennsylvania, have invented and produced a new and original Design for a Flag, of which the following is a specification, reference being had to the accompanying drawing, showing a part thereof.

10 The leading feature of my design for a flag is the body of the same of the form of a flag, and a border therefor of the form of a horse-shoe.

In the drawing—A designates the body of a flag, and B designates a border therefor, the same being of the form of a horse-shoe. The flag shown is that of the United States.

What I claim is—

The design for a flag, substantially as shown and described.

WILLIAM BRADLY.
